UNITED STATES PATENT OFFICE

94,253

DESIGN FOR A GAME DEVICE

Dudley H. Wiggins and William T. Anderson,
Indianapolis, Ind.

Application October 3, 1934, Serial No. 53,472

Term of patent 3½ years

To all whom it may concern:

Be it known that Dudley H. Wiggins and William T. Anderson, citizens of the United States, residing at Indianapolis, in the county of Marion and State of Indiana, respectively, have invented a new, original, and ornamental Design for a Game Device, of which the following is a specification.

Reference is had to the accompanying drawing, forming part thereof, in which;

We claim:

The ornamental design for a game device, as shown.

DUDLEY H. WIGGINS.
WILLIAM T. ANDERSON.
